HAIRPIN DISPENSER

Betty Steinberg, Los Angeles, Calif.

Application February 20, 1950, Serial No. 145,266

7 Claims. (Cl. 312—67)

1

The present invention relates to an improved dispenser for hairpins, bobby pins, paper clips and the like, the dispenser shown herein being an improvement in the dispensers shown and claimed in my copending applications, Serial No. 41,930, filed August 2, 1948, now Patent No. 2,544,114 issued March 6, 1951, for Hairpin Dispenser, and Serial No. 86,795, filed April 11, 1949, now Patent No. 2,602,720 issued July 8, 1952, for Hairpin Dispenser.

It is desirable that articles such as hairpins, bobby pins and the like be maintained in a predetermined position, being a readily accessible one, and of such nature that there is little likelihood that the appearance of a woman's dressing table might be impaired in day to day use of such articles, and such that the necessity of searching for such "lost" pins is greatly reduced.

The dispenser as shown and claimed herein is generally of the type shown and claimed in my above mentioned copending patent applications, and incorporates small magnets associated with hooks which are arranged to dispense hairpins, bobby pins and the like from a pile in which they are randomly disposed.

A feature of the present dispenser is the incorporation and association of a mechanical hooked member with magnetic means to assure more positive action of the dispenser and without the necessity that the hairpins be of special magnetic construction, another of the important features of the present invention being that conventional present day hairpins and bobby pins may be dispensed from my improved dispenser.

It is therefore an object of the present invention to provide an improved arrangement whereby the aforesaid desirable results may be obtained.

Another object of the present invention is to provide a dispenser of this character which incorporates magnetic means associated with mechanical hooks for dispensing hairpins but which does not require for its operation specially magnetized or fabricated hairpins or bobby pins, the dispenser being effective to dispense hairpins, bobby pins and the like of standard wire construction.

Still another object of the present invention is to provide an improved dispenser arranged to dispense in orderly fashion hairpins, bobby pins, and the like disposed in random fashion.

A further object of the present invention is to provide an improved dispenser of this character which has only one movable part, namely, a magnetic structure movable between two positions.

2

A further object of the present invention is to provide an improved dispenser of this character which requires a minimum number of movable elements and which avoids the necessity of a movable stripping element to strip the magnetizable objects from the magnetic structure after such objects have been extracted from a compartment.

Yet a further object of the present invention is to provide an improved dispenser of the character described, characterized by the fact that the direction of the magnetic forces between the magnetic structure and the magnetizable object is such that the magnetizable object may be stripped from the magnetic structure on the development of a relatively small frictional force between the magnetizable object and a member relatively stationary to the magnetic structure.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is a view in side elevation of an improved dispenser embodying the features of the present invention.

Figure 2 is a view in front elevation taken in the direction indicated by the arrows 2—2 in Figure 1, and with a forward portion of the dispenser broken away to show some internal structure.

Figures 3 and 4 are views taken on corresponding lines 3—3 and 4—4 in Figure 2, it being noted that Figure 3 is a sectional view whereas Figure 4 is a view in plan elevation of the dispenser.

Figure 5 is a sectional view similar to the sectional view shown in Figure 3, but with the magnetic extractor shown moved in its upward position and correspondingly with its control lever in depressed position, the upward position of such control lever being indicated by dotted lines; Figure 5 also showing in dotted lines the pivoted hairpin tray in a convenient outward position wherein it is placed when, for example, it is desired to refill the pivoted tray.

Figures 6 and 7 are views taken on corresponding lines 6—6 and 7—7 in Figure 3, it being noted that Figure 7 corresponds also to a view taken as indicated by the lines 1—1 in Figure 6.

Figure 8 is a perspective view of the pivoted hairpin tray or compartment storage bin shown in the previous figures, and

Figure 9 is a perspective view of the magnetic extractor which is shown in its lowermost position in Figure 3 and in its uppermost position in Figure 5.

The hairpin dispenser operates to dispense articles, for example, hairpins 10 randomly disposed in the compartment storage tray 11 in orderly fashion upon first pressing downwardly on the spring biased manually operable control lever 12, to move such lever 12 from its uppermost position shown in Figure 3 to its lowermost position shown in Figure 5, and thereafter releasing such control lever 12 to allow the control lever 12 and actuated extractor 14 to return to its initial position under the influence of the coil tension spring 15.

The dispenser comprises essentially a stationary base 20 with a pair of parallel upstanding walls 21, 22 (Figure 4) which have guide members 21A, 22A thereon respectively to provide guided movement of the magnetic extractor 14, which is movable in a direction inclined slightly with respect to the vertical. The extractor 14 is normally biased downwardly by the coil tension spring 15 having one of its ends attached, as shown in Figures 3 and 5, to a suitable abutment 14A such as, for example, a rivet, and its other end attached to the stationary pin 20A which may either be affixed to the base 20 or which may comprise simply an elongated rod having a length greater than the diameter of the hole 20B in the base 20 through which the spring 15 passes. In the latter case, the rod 20A is maintained in position since the spring 15 is prestressed at all times to cause the rod 20A to be pressed against the underside of the base 20.

This extractor 14 is linked to the control lever 12, so that movement of the control lever 12 results in movement of the extractor 14. The particular means whereby control lever 12 is linked to the extractor 14 is of the following construction.

The lever having the general reference numeral 12 includes a manually engageable member 12A (Figure 4) having its opposite ends affixed to one end of lever members 12B, 12C respectively (Figure 4), the other ends of the lever members 12B, 12C having, as shown in Figure 1, clearance or lost motion slots 12D through which pins 24 pass. The pins 24 pass also through clearance slots 25, 26 (Figure 1) in the supports 21, 22, and are anchored in the extractor 14. These lever members 12B, 12C are pivoted about pivot pins 27, 28, which pass through a point intermediate the ends of such lever members 12B, 12C, so that downward movement of the lever member 12 results in upward movement of the extractor 14.

The magnetic extractor 14, shown in perspective in Figure 9, has mounted thereon a plurality of Alnico magnets 30 encased in cylindrical housings 30A. These housings 30A, in turn, are cemented or affixed in other similar manner to the top plate 30B. This top plate 30B overhangs the front plate 30C a small distance to provide a ledge 30E. It is noted that the magnets 30 and their casings 30A terminate at the edge of such ledge 30E with each one of the magnets 30 adjacent a hook 32. These hooks 32 are formed by triangularly shaped pieces 34 of plastic material which is cemented both to the top plate 30B and the front plate 30C, with a portion of such triangular piece extending forwardly of the front edge of the ledge 30E, thereby effectively forming a projecting hook or abutment which, as explained

in greater detail hereinafter, is in a position to engage and to carry a hairpin upwardly after such hairpin is first attracted by the corresponding magnet 30.

The storage bin or receptacle 11 is shown in perspective in Figure 8, and includes simply a compartmented rectangular box with a handle member 11A thereon. This rectangular box 11 is pivotally mounted by means of pins 40A and 41A on the stationary upwardly extending plates 21, 22, so as to swing from the full line position in Figure 5 to the dotted line position. It is noted that in the full line position the upwardly extending wall of the box 11 is inclined slightly away from the vertical to allow hairpins 10 disposed therein to gravitate downwardly against its backside 11C. It is noted further that such backside 11C, preferably of plastic material, is routed out at 11E to provide a clearance slot for the triangularly shaped pieces 34 on the extractor 14 in its lowermost position, so that, as shown in Figures 3, 7 and 9 the forward edge of the hook or abutment member 32 projects slightly forward of the interior face of the back wall 11C of the container 11, the distance which such abutment 32 projects being slightly greater than the diameter of the wire forming a hairpin 10.

It will be appreciated that while the hairpin storage box 11 is formed with four compartments and with a corresponding number of magnets 30 and associated hook or abutment members 32, the precise number may be increased or decreased, since the method of extraction does not depend upon any particular number of compartments.

In operation of the device, the hairpins 10 are disposed in the various compartments of the pivoted storage receptacle 11, which may be pivoted outwardly to the dotted line position shown in Figure 5 for convenient filling of the same. After the chambers are filled, the container 11 is swung inwardly to its full line position shown in Figure 5 so that the hairpins 10 may rest against the back wall 11C of the container, from where they may be extracted and dispensed one at a time upon repeated operation of the lever member 12.

When the hairpins 10 are in the position shown in Figure 3, the one adjacent the wall 11C is drawn upwardly due to magnetic attraction produced by the magnet 30, and such hairpin in its travel upwardly engages and passes over the triangular piece 34 which is preferably triangular to offer a limited amount of resistance to the motion of the hair pin which at this time is moved solely under the influence of magnetism to a position above the hook or abutment 32 as shown in dotted lines in Figure 6. In its movement under the influence of magnetism, the hairpin is drawn upwardly through the restricted opening 41 (Figure 7). It is noted that the vertical component of the magnetic force set up by the magnet is sufficient to attract a pin and to draw it upwardly until it abuts the said magnet, such vertical component of the magnetic force being sufficiently large in intensity to overcome any resistance offered to such movement by the portions 32 and the sides of the opening 41. Then, upon subsequent upward movement of the extractor 14, the magnetic attraction forces exerted on the hairpin may be such to cause the hairpin to rise upwardly with the extractor 14 with the hair pin clinging to the magnet 30 as shown in dotted lines in Figure 6. However, such magnetic forces need not be very large since

even though it were insufficient to maintain the hair pin in clinging position and the hair pin slid on the magnet face when the extractor 14 is moved upwardly, the U-bend portion of the attracted hairpin 10 is engaged by and carried upwardly by the hooked portion or abutment 32, referred to also herein as abutment means 32. In the event that more than one hairpin is attracted and drawn upwardly through the aperture 41 by the magnet 30 since, the abutment 32 projects a distance to accommodate only one hairpin, the abutment 32 is capable of lifting only one hairpin at a time. To further assure the extraction or dispensing of only one hairpin, the stationary cross piece 40, affixed at its opposite ends to the stationary vertical supporting members 21, 22, is provided with rectangularly shaped apertures 41 of a width only slightly greater than the diameter of the wire forming the hairpin 10.

Besides performing this function, the apertured portions 41 serve also to frictionally contact the extracted hairpin to maintain such hairpin in its uppermost position after the extractor 14 is allowed to move downwardly under the influence of tension spring 15. In other words, the width and length of the rectangular apertured portion 41 serves to assure the passage therethrough of only one hairpin at a time, but the length of such apertured portion 41 is such that after the bowed portion or U-bend portion of the hairpin 10 passes therethrough the remaining portion of the hairpin, in its passage through the apertured portion 41, resiliently engages the walls forming such apertured portion 41 to prevent a lifted hairpin from falling downwardly back into the receptacle 11. Also, to insure the retention of the extracted hairpin in its elevated position after the extractor 14 is allowed to move downwardly, there is provided a horizontally extending ledge or shelf 11H on the back surface 11C, such shelf 11H being spaced such that the free ends of the extracted hairpin abut the ledge 11H to prevent its downward movement, it being noted that the width of the shelf 11H is somewhat greater than the diameter of the wire of which the hairpin is made.

It is noted that the device described depends for its operation on the production of magnetic forces between the magnet 30 and the U-bend or bowed portion of the article 10. It is necessary that these magnetic forces result in the movement of the hairpin 10 from its full line position shown in Figure 6 to its dotted line position therein, wherein the hairpin directly contacts the end of the magnet 30.

It is observed that the direction of magnetization is in the longitudinal direction of the magnet 30 and that such direction of the magnetization is perpendicular to the direction of movement of the magnetic extractor 14. It is observed that this magnet 30 is desirably of Alnico to produce high magnetic forces for the intended result. Because these magnetic forces are relatively high, there is a tendency for the hairpin 10 to be attracted and maintain against the underside of the ledge 30E. This tendency, however, is overcome due to the particular configuration of the abutment means 32, which presents an upwardly inclined cam surface to a hairpin as it moves upwardly and over such abutment means 32.

Furthermore, while the magnet 30 is of sufficient strength to produce this described movement, the magnet 30 is not sufficiently strong

to cause a hairpin to be moved an appreciable distance after the magnetic structure 14 is moved downwardly from its position shown in Figure 5. In other words, the frictional forces developed between the hairpin 10 and the walls of apertured portion 41 is greater, in the raised position of the hairpin, than the forces exerted in the same direction between the hairpin 10 and the magnet 30, with the result that the hairpin 10 is maintained in its elevated position upon subsequent downward movement of the magnetic structure 14 from its elevated position shown in Figure 5.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a hairpin dispenser of the character described for hairpins having a U-bend therein connecting legs thereof, comprising: a compartment within which magnetizable objects are placed, said compartment being disposed adjacent a member having an apertured portion through which said objects may be passed in single file, a magnetic structure mounting a magnet cooperating with said U-bend and movable in a predetermined path to a position adjacent said apertured portion through which said objects may be withdrawn by the magnetic attraction of said magnetic structure, abutment means on said magnetic structure over which said U-bend is drawn by said magnetic structure, and said apertured portion having walls engageable with said legs.

2. A dispenser of the character described for magnetizable objects having a U-bend therein, comprising: a compartment for the storage of said magnetizable objects, a member having an aperture of dimensions commensurate with the cross-section of one of said objects through which said objects are adapted to pass, one at a time, a magnetic structure mounting a magnet movable from an elevated position to a lowered position adjacent said aperture to attract and to lift through said aperture said magnetizable objects, abutment means mounted for movement with said magnetic structure, said abutment means being disposed between said magnet and said compartment and adapted to engage and to support one of said magnetizable objects at its U-bend.

3. A dispenser of the character described having a compartment for the storage of magnetizable objects with a U-bend in each object, a member having an aperture of cross-sectional dimensions commensurate with the cross-sectional dimension of one of said objects through which said objects are adapted to pass, one at a time, a magnetic structure mounting a magnet movable from an elevated position to a lowered position adjacent said aperture to attract and to lift an object through said aperture, and abutment means movable with said magnetic structure, adapted to engage the U-bend and to carry upwardly a magnetizable object originally attracted by said magnet.

4. In a dispenser of the character described having a compartment for the storage of magnetizable hairpin objects with a U-bend in each object connecting the legs thereof, a member

having an aperture of cross-sectional dimensions commensurate with the cross-sectional dimension of one of said objects through which said objects are adapted to pass, one at a time, a magnetic structure mounting a magnet movable from an elevated position to a lowered position adjacent said aperture to attract and to lift an object through said aperture, abutment means movable with said magnetic structure adapted to engage the U-bend and to carry upwardly a magnetizable object originally attracted by said magnet, said aperture having walls thereof adapted to frictionally engage the legs of said magnetizable object to maintain it in elevated position against gravity forces and also against magnetic forces produced by said magnet.

5. A dispenser of the character described having a compartment for the storage of magnetizable objects with a U-bend therein connecting legs thereof, a member having an aperture of cross-sectional dimensions commensurate with the cross-sectional dimension of one of said objects through which said objects are adapted to pass, one at a time, a magnetic structure mounting a magnet movable from an elevated position to a lowered position adjacent said aperture to cooperate magnetically with said U-bend to attract and to lift an object through said aperture, and the wall of said aperture being engageable with said legs and effective when said magnetic structure is in its uppermost position to allow said magnetic structure to again descend to its lowered position with the object remaining in substantially its uppermost position.

6. A dispenser of the character described for magnetizable objects having a U-bend therein connecting legs thereof, comprising: a compartment within which magnetizable objects are placed, a member having an apertured portion of cross-sectional dimensions commensurate with the cross-sectional dimension of one of said objects through which said objects may be passed in single file, a magnetic structure mounting a magnet cooperating magnetically with said U-bend and movable from a normal position adjacent said apertured portion through which said objects may be withdrawn by the magnetic at-

traction of said magnetic structure on said U-bend, and means engageable with said legs and effective upon movement of said magnetic structure from a retracted position to said normal position for removing the magnetizable objects therefrom.

7. A dispenser of the character described, comprising: a receptacle for the storage of magnetizable hairpin objects with a U-bend therein connecting the legs thereof, a member having an aperture of cross-sectional dimensions commensurate with the cross-sectional dimension of one of said objects through which said objects are adapted to pass, one at a time, a magnetic structure mounting a magnet movable from an elevated position to a lowered position adjacent said aperture to attract and to lift through said aperture said magnetizable objects, said magnet being magnetized in a direction substantially perpendicular to the direction of movement of said magnetic structure, abutment means movable with said magnetic structure and disposed between said magnet and said aperture to engage said U-bend, said abutment means having a portion thereon engageable with the U-bend of said object with a dimension slightly greater than the effective width of said object to thereby assure contact with only one of said objects, said abutment means comprising an upwardly inclined cam member to assure movement of an object over said abutment into engagement with said magnet, and said aperture having walls cooperating with the legs of an object partially withdrawn therefrom to develop frictional forces therebetween in the longitudinal direction of said object greater than the forces of attraction between said object and said magnet in said longitudinal direction whereby said object may be stripped from the magnetic structure.
